US0D1010332S

(12) United States Design Patent (10) Patent No.: US D1,010,332 S
(45) Date of Patent:  Jan. 9, 2024

(54) MASSAGE ARMCHAIR

(71) Applicant: Fuzhou Feiwo Trading Co., Ltd.
Fuzhou (CN)

(72) Inventor: Nan Fang, Fuzhou (CN)

(73) Assignee: FUZHOU FEIWO TRADING CO., LTD, Fuzhou (CN)

() Term: 15 Years

(21) Appl. No.: 29/786,722

(22) Filed: Jun. 2, 2021

(51) LOC (14) Cl. 06-01

(52) U.S. Cl.

CLAIM

The ornamental design for a massage armchair, as shown and described.

DESCRIPTION

FIG. 1 is a front and right side perspective view of a massage armchair showing my new design;

FIG. 2 is a front and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is bottom plan view thereof.

The broken lines in the drawings depict portions of the massage armchair that form no part of the claimed design.

1 Claim, 8 Drawing Sheets
